United States Patent Office

Des. 191,133
Patented Aug. 15, 1961

191,133

IRON HOLDER

Frederick Marx, Sr., 2205 N. 7th Ave., Lake Worth, Fla.

Filed Feb. 27, 1961, Ser. No. 64,078

Term of patent 14 years

(Cl. D49—6)

The figure is a perspective view of an iron holder, showing my new design.

The side not shown is substantially like the side shown.

I claim:

The ornamental design for an iron holder, substantially as shown and described.
